(57) **CLAIM**

The ornamental design for a cushion for patient interface, as shown and described.

DESCRIPTION

FIG. 1 is a front perspective view of a cushion for patient interface showing a first embodiment of our new design;

FIG. 2 is a front view thereof;

FIG. 3 is a rear view thereof;

FIG. 4 is a top view thereof;

FIG. 5 is a bottom view thereof;

FIG. 6 is a left side view thereof;

FIG. 7 is a right side view thereof;

FIG. 8 is a reverse perspective view thereof;

FIG. 9 is a front perspective view of a cushion for patient interface showing a second embodiment of our new design;

FIG. 10 is a front view thereof;

FIG. 11 is a rear view thereof;

FIG. 12 is a top view thereof;

FIG. 13 is a bottom view thereof;

FIG. 14 is a left side view thereof;

FIG. 15 is a right side view thereof; and,

FIG. 16 is a reverse perspective view thereof.

The stippled sections of the cushion for patient interface represent contrasting materials or appearances.

The heavily stippled area of the cushion for patient interface represents contrasting materials to the lightly stippled area. The broken lines in the drawings depict portions of the cushion for patient interface that form no part of the claimed design.
